United States Patent

Des. 234,718
Patented Apr. 1, 1975

234,718

MICROFICHE VIEWER

Stephen G. Hauser, Tarzana, Ralph M. Bergo, Playa del Rey, and John Goodin, Long Beach, Calif., assignors to UMF Systems Incorporated, Los Angeles, Calif.

Filed Aug. 8, 1973, Ser. No. 386,601

Term of patent 14 years

Int. Cl. D16—03

U.S. Cl. D61—1 N

FIG. 1.

FIG. 2.

FIG. 1 is a front and right side perspective view of a microfiche viewer showing my new design; and

FIG. 2 is a front and left side perspective view thereof, the rear and top being plain and unornamented.

We claim:

The ornamental design for a microfiche viewer, substantially as shown and described.
